UNITED STATES PATENT OFFICE

WALTER J. CLEMENT, OF UTICA, NEW YORK, ASSIGNOR TO THE BOSSEET CORPORATION, OF UTICA, NEW YORK, A CORPORATION OF NEW YORK

ROTARY HAMMER MILL

Application filed March 10, 1928. Serial No 260,735.

This invention relates to mills of that type wherein a plurality of hammers are carried by a rotary shaft or drum, the hammers being caused to swing through a material receiving chamber in circular paths by rapid rotation of the drum or shaft. In order that such a mill may operate smoothly it is important that the hammers be mounted in both static and dynamic balance. It is also desirable 10 that the hammers shall be so arranged as to tend to prevent the material being operated upon from lodging in those portions of the chamber inaccessible to the action of the hammers, this being particularly likely in mills 15 as heretofore constructed at the ends of the chamber beyond the end hammers.

This invention has for its object, therefore, the arrangement of hammers by which these desiderata may be obtained. The hammers 20 are arranged therefore according to this invention in staggered formation, defining by successive hammers in sequence striking paths converging from the ends of the chamber toward a mid position, the hammers diametrically opposite to each other being positioned at or near the same points longitudinally of the rotational axis. Even though the hammers should be balanced statically it is found in practice that should those on one 30 side of the axis be offset by substantial amounts longitudinally of the axis from those diametrically opposite, centrifugal force developed in operation set up tremendous bending stresses which unbalance the mill dynamically and cause excessive and even dangerous vibration.

For a more complete understanding of this invention reference may be had to the accompanying drawings in which

40 Figures 1 and 2 are developments of arrangements of hammers angularly spaced six about the rotational axis.

Figures 3 and 4 are end elevations of hammer assemblies, corresponding to Figure 1, but showing different types of hammers in the two figures.

45 Figures 5 and 6 show other arrangements for 6 and 8 hammer spacing, respectively.

50 Figures 7 and 8 are views similar to Fig-

ures 3 and 4 but showing eight hammer angular spacing.

Referring to Figures 1, 3 and 4 the rotor comprises a plurality of disks 1 arranged in spaced relation lengthwise of the shaft 2 to which they are fixed for simultaneous rotation by any suitable means, as shown, the shaft having a flat portion 3 thereon with which a mating portion on each of the disks engages. Arranged in circular series about the shaft 2 and parallel therewith are rods 4. These rods extend through the several disks and serve to carry the hammers. In the form shown in Figure 3 the hammers 5 are fixed in pivotal relation to the rod 4, while in Figure 4 each of the hammers 6 is shown as provided with a slot 7 through which the rods 4 pass. When the mill having hammers such as shown in Figure 4 is in operation, these hammers fly out to the limits of engagement between the rods 4 and slots 7 where they are held by centrifugal force. As shown in Figures 1, 3 and 4 six rods 4 are employed, though as will be seen later other even numbers of rods may be employed if desired.

70 The hammers may be arranged on the different rods 4 as shown in Figure 1. For example, on rod 4^a a pair of hammers are arranged in the spaces between the end pair of disks 4. The rod 4^b has a pair of hammers each of which is positioned in the fourth space inwardly from the end disk 1. The rod 4^c has its two hammers spaced inwardly from the ends of the rotor in the fifth spaces. The rod 4^d has its hammers arranged in the second spaces, the rod 4^e its hammers arranged in the third spaces, and the rod 4^f its hammers arranged in the sixth spaces. The rod 4^a with its hammers is diametrically opposite to the rod 4^d with its hammers and it will be noted that the hammers on these two rods are positioned only one space from each other, the hammers on the rod 4^a being positioned inwardly one space further than the hammers on the rod 4^d. The hammers on the rod 4^b, which is opposite to the rod 4^e, are positioned inwardly one space further than the hammers on the rod 4^e, while the hammers on the rod 4^c are positioned one space 75 80 85 90 95 100

further outwardly than the hammers on the rod 4^c and are diametrically opposite thereto. It will thus be seen that while the hammers on diametrically opposite rods are not in exact alinement lengthwise of the rotor they do not depart by more than one space from exact alinement. The hammers on one of these rods are positioned nearer to the ends than on the one diametrically opposite while the 10 rods on either side thereof have their hammers positioned further inwardly than those opposite thereto. By this means a very close approximation to dynamic balance of the rotor assembly may be produced, attention of course being paid to the balancing of the 15 weights of the hammers for static balance. It is found that where the hammers at diametrically opposite points are positioned at substantially different distances along the 20 length of the shaft, heavy vibration is sure to result when the rotor is operated at the desirable high speeds.

It should also be noted that the hammers on the rods 4^a and 4^b and 4^c are arranged in 25 two series converging from the ends of the rotor toward the center in the direction of rotation of the rotor, that is, the more widely spaced hammers are followed by those progressively less widely spaced. Similarly the 30 hammers on the rods 4^d, 4^e and 4^f converge from the ends toward the center of length of the rotor. It is found in practice that this converging formation and arrangement of the hammers tends to feed the material inwardly from the ends of the mill toward the 35 center, this action being more pronounced where the convergence is the more gradual, there being a tendency for the material otherwise to lodge at the ends of the mill where it is out of reach of the hammers. Certain of 40 the hammers are also arranged in series some of which at least diverge in the direction of rotation or converge in the opposite direction to that of the rotation. For example, 45 the hammers on the rod 4^d are more widely spaced than those on the adjacent rod 4^e and the hammers on the rod 4^e are more widely spaced than those on the adjacent rod 4^f, but it will be noted that this divergence in the 50 direction of rotation is much steeper than the convergence of the other series in the same direction of progression comprising the hammers on the rods 4^a, 4^b, 4^c and 4^d, 4^e, 4^f and this divergence is in fact too steep to produce 55 any substantial movement of the material being ground outwardly from the center of length of the mill. This arrangement is found in practice to result in marked improvement in the operation of the mill.

60 In Figure 2 is shown an arrangement using six hammer supporting rods 10 as in Figure 1, but with more disks and consequently room for more hammers. In this arrangement it will be noted that instead of two hammers on each rod, each rod carries six ham-

mers and that these hammers are arranged in a plurality of converging series from the ends of the rotor toward the center, one set of such series beginning at the rod 10^a and another set of such series beginning at the rod 10^d. In each set of three rods 10^a, 10^b and 10^c and 10^d, 10^e, 10^f it will be noted that there are three lines of hammers on each side of the center arranged in converging series and that certain series of the one group of three rods 75 is continued in the other group of three rods in the same general line of convergence. For example, one such line is indicated by the dot and dash line a—b, c—d. Each complete series or line passes one and a half times about 80 the rotor in passing from its extreme outward position to its extreme inward position. This may be contrasted with the showing of Figure 1 in which each series is complete in one half of a circumference of the rotor, there 85 being three hammers in each converging series, whereas in the showing of Figure 2 there are nine hammers in each series. With the arrangement shown in Figure 2 the hammers on diametrically opposite rods are located in 90 identically the same spaces so that there is a substantially exact rotation or dynamic balance instead of the closely approximate rotational balance in the form shown in Figure 1. It will be noted that in each instance 95 the series of hammers lie in lines arranged at an angle to the perpendicular to the axis of rotation of the rotor.

In Figure 2 it will be noted that the hammers are also arranged in diverging lines in 100 the direction of rotation or converging lines in the opposite direction, but the divergence in the direction of rotation is steeper than the convergence in the other series in the same direction. The lines of divergence between the center and ends are complete in 5 hammers—for example, the inner hammers on the bolt 10^f through those on bolts 10^a, b and c to the outer hammers on the bolts 10^d— 105 while the lines of convergence require 9 hammers. For example, the successive hammers in each series line are in adjacent spaces to each other in the direction of presentation in the normal rotation of the mechanism, while in the opposite direction they are spaced two 110 spaces from each other, the slope of the lines being thus much steeper against the normal direction of rotation than in this direction of rotation. This arrangement also has the advantages of tending to move the material 115 from the ends of the rotor toward its center and when in static balance may also be in exact rotational balance.

In Figure 5 a further modification is shown 120 in which the six hammer carrying rods 20^a, 20^b, 20^c, 20^d, 20^e and 20^f each support eight hammers, these being arranged in converging 125 series of twelve hammers each in the direction of rotation and each completing two complete circumferences of the rotating mechanism. 130

One complete series is shown by the dot dash line *uv, xy*. The hammers of each series are spaced from each other progressively by a single disk being in successive spaces between 5 the disks in the order of their presentation in the normal direction of rotation of the rotor. In the reverse or diverging direction the hammers of adjacent rods are two spaces apart and the series is complete in either 4 or 10 5 hammers so that here also is a non-symmetrical arrangement of converging and diverging lines of hammers. The rods at diametrically opposite points in this construction have their hammers arranged identically in so far 15 as their spacing lengthwise of their axis of rotation is concerned and are therefore in dynamic balance.

In Figures 6, 7 and 8 are shown such mechanisms in which eight instead of six hammer 20 supporting rods 30 are employed. The hammers as shown in Figures 7 and 8 correspond in construction to those illustrated in Figures 3 and 4 respectively. In Figure 6 each of the rods carries a single pair of hammers. The 25 hammers on the rod 30^a are arranged in the end spaces, while those on the opposite rod 30^e are arranged in the second spaces from the ends. The hammers on the rods 30^b are arranged on the fourth spaces, while the hammers on the diametrically opposite rod 30^f are arranged in the third spaces. The hammers in the rods 30^c are arranged in the fifth spaces, while the hammers 30^g are arranged in the 30 sixth spaces. The hammers on the rod 30^d are arranged in the eighth spaces, and the hammers on the rod 30^h are arranged in the 35 seventh spaces. In this arrangement, as in the arrangement shown in Figure 1, the hammers on opposite rods are not in exactly the same relation axially but differ therefrom by a single space only and that where this difference is in one direction, as between one set of opposite bars, it is in the opposite direction 40 in the case of the diametrically arranged bars next adjacent thereto.

In the arrangement shown in Figure 6 for eight hammer supporting rods each line of the converging series comprises four hammers, each series being complete in half a 50 circumference of the assembly, in this respect being similar to Figure 1. The divergence in the direction of rotation is only between the hammers on rods 30^e and 30^e and 30^b 30^a and is complete in 2 hammers. Where more hammers are employed the series may be made 55 correspondingly longer similarly to the showings of Figures 2 and 5. It will also be noted that this arrangement is unsymmetrical in convergence and divergence as in the other 60 forms heretofore described.

Where the number of spaces between the disks is the same as the number of hammers, as shown in Figures 1 and 6, it is not possible 65 to have the hammers on one rod positioned identically with those on the diametrically

opposite rod, but they need be relatively offset from each other one space only, and by reversing the direction of such offsetting in the next adjacent rods the relatively small unbalancing effects of such offset are largely 70 neutralized. When the number of hammers is an even multiple of the number of spaces, as shown in Figures 2 and 5, the diametrically opposite hammer arrangement may be identical. 75

Having thus described certain embodiments of this invention by way of example, it should be evident to those skilled in the art that various changes and modifications might be made therein without departing from its 80 spirit or scope as defined by the appended claims.

I claim:

1. A mechanism of the class described comprising a rotor, and hammers arranged in a 85 multiplicity of series circumferentially of said rotor, the hammers in certain series being arranged in circumferential lines converging from the ends toward the center of length of said rotor in the direction of rotation thereof, certain of said hammers being arranged in circumferential lines diverging from the center of length toward the ends thereof in said direction but at a different slope than that of said converging lines, the 90 hammers diametrically opposite to each other being arranged close to the same position lengthwise of said rotor.

2. A mechanism of the class described comprising a rotor, and hammers arranged in a 100 multiplicity of series circumferentially of said rotor, the hammers of each series being arranged in circumferential lines inclined to the perpendicular to the axis of rotation of said rotor in one direction and unsymmetrically in opposite directions of inclination, 105 said hammers being in substantially static and dynamic balance.

3. A mechanism of the class described having a rotor comprising a shaft and a plurality of disks arranged concentrically on said shaft in spaced relation, rods arranged in circular series in said disks coaxially with said shaft, and hammers carried by said rods in the spaces between adjacent disks, said hammers being arranged in a multiplicity of circular 110 series in circumferential lines, some converging and some diverging in the same direction of progression, the convergence being at a different angle from the divergence, the hammers on diametrically opposite rods being arranged not further than one space from each other axially of said rotor.

4. A mechanism of the class described having a rotor comprising a shaft and a plurality of disks arranged concentrically on said shaft in spaced relation, rods arranged in circular series in said disks coaxially with said shaft, and hammers carried by said rods in the spaces between adjacent disks, said 115 120 125 130

hammers being arranged in a multiplicity of circular series in circumferential lines, some converging and some diverging in one direction of progression, the convergence being 5 at a different angle than the divergence, the hammers on diametrically opposite rods being arranged not further than one space from each other axially of said rotor, any differences of spacing of said hammers on diamet- 10 rically opposite rods being in reversed direction in circumferentially adjacent diametrically opposite rods.

5. A mechanism of the class described having a rotor comprising a shaft and a plurality 15 of disks arranged concentrically on said shaft in spaced relation, rods arranged in circular series in said disks coaxially with said shaft, and hammers carried by said rods in the spaces between adjacent disks, said hammers 20 being arranged in a multiplicity of circular series in circumferential lines converging from the ends toward the center of length of said rotor and in lines diverging at steeper angles than the converging lines, the ham- 25 mers on diametrically opposite rods being arranged not further than one space from each other axially of said rotor, any differences of spacing of said hammers on diametrically op- 30 posite rods being in reversed direction in circumferentially adjacent diametrically opposite rods.

6. A mechanism of the class described having a rotor comprising a shaft and a plurality 35 of disks arranged concentrically on said shaft in spaced relation, rods arranged in circular series in said disks coaxially with said shaft, and hammers carried by said rods in the spaces between adjacent disks, said hammers being arranged in a multiplicity of cir- 40 cular series in circumferential lines some con- verging from the ends toward the center of length of said rotor and some diverging in one direction of progression, the convergence be- 45 ing at a different angle from the divergence.

45. In testimony whereof I have affixed my signature.

WALTER J. CLEMENT.
